(57) **CLAIM**

The ornamental design for a visual display unit for vehicle, as shown and described.

DESCRIPTION

FIG. 1 is a rear perspective view of the visual display unit for vehicle, in accordance with the present invention;

FIG. 2 is a front perspective view thereof;

FIG. 3 is a front elevation view thereof;

FIG. 4 is a left side elevational view thereof, the right side being a mirror image thereof; and,

FIG. 5 is a top plan view thereof.

The broken lines illustrate portions of the visual display unit for vehicle which form no part of the claimed design.
